UNITED STATES PATENT OFFICE.

SIDMAN RUSKIN, OF CHICAGO, ILLINOIS, ASSIGNOR TO F. H. NOBLE & COMPANY, OF CHICAGO, ILLINOIS, A CORPORATION OF ILLINOIS.

SHEET-METAL FASTENER.

Application filed July 24, 1920. Serial No. 293,796.

To all whom it may concern:

Be it known that I, SIDMAN RUSKIN, a citizen of the United States, residing at Chicago, in the county of Cook and State of Illinois, have invented certain new and useful Improvements in Sheet-Metal Fasteners, of which the following is a specification.

My invention relates to sheet metal fasteners intended to serve as a means for temporarily attaching together and holding in a group a number of separate loose sheets of paper, or similar articles. The object of my invention is to provide a simple, serviceable article of this kind which may be cheaply manufactured, having an attractive appearance and with its engaging member so formed and constructed as to facilitate its application to a group of papers, and which will hold the papers securely and be highly desirable and useful for the purposes for which it was designed. My invention resides in the particular form and construction of the parts of the fastener, and more particularly in the arcuate flared shape of the end of its tongue portion, as herein-after described and as more particularly pointed out in the appended claims.

In the accompanying drawing, Figure 1 is a front or face view of my improved fastener; Fig. 2 is a section of the same on the line 2—2 of Fig. 1; and Fig. 3 is a rear view of the fastener, showing in dotted lines the position in which the edge of a group of papers is presented to the tongue member in applying the fastener to them.

My novel fastener or paper clip is formed of sheet metal possessing a considerable degree of inherent elasticity, such as sheet brass, and comprises a flat front or body portion A, which may conveniently be of the oval shape illustrated, and which forms a field which may be stamped in bas relief with a design or emblem of any desired and suitable character, such as a trade mark

or advertising device or emblem, and which may be colored by the application of enamel, or plated, or otherwise decorated as desired. Connected to the top edge of the portion A is an integral tongue B which is folded from 50 an open loop of the portion A, and the end C of which is flared outwardly from an arcuate bead D near the end of the tongue contacting the contiguous rear surface of the part A near its lower edge. The curved 55 and flared shape of the end of the tongue is the characteristic and essential feature of my invention, and renders it very easy to apply the clip to a group of papers when the edge of the group is applied to an intermediate point in the curve,—as indicated by the dotted line E in Figure 3—thus enabling a comparatively stiff clip to be applied to a comparatively thin bundle of sheets without tearing them. My improved 60 fastener is therefore particularly secure and serviceable, as well as highly attractive and desirable as an advertising novelty.

I claim:

1. As an article of manufacture, a fastener 70 formed of elastic sheet metal and comprising a flat front portion and a backwardly folded integral engaging tongue, the end of said tongue being outwardly flared along an arcuate path.

2. As an article of manufacture, a fastener formed of elastic sheet metal and comprising a relatively broad flat front portion and a backwardly folded integral tongue connected with a said front portion by an 80 open loop, the end of said tongue being outwardly flared along an arcuate path.

3. As an article of manufacture, a fastener formed of elastic sheet metal and comprising a flat front portion and a backwardly folded integral engaging tongue, said tongue being formed adjacent its end with a transverse arcuate bead and its end flared outwardly from said bead.

SIDMAN RUSKIN.
